UNITED STATES PATENT OFFICE.

EDWARD M. REEVES, OF CHICAGO, ILLINOIS.

AUTOMOBILE-SPRING COMPRESSOR.

1,382,801.

Specification of Letters Patent. Patented June 28, 1921.

Application filed April 21, 1920. Serial No. 375,506.

To all whom it may concern:

Be it known that I, EDWARD M. REEVES, a citizen of the United States of America, and a resident of Chicago, in the county of Cook, 5 State of Illinois, have invented certain new and useful Improvements in Automobile-Spring Compressors, of which the following is a specification.

This invention relates to that class of 10 compressing machines adapted for the convenient handling of the spring members of an automobile in the assembly, removal and replacement of the same, and the present improvement has for its object,

15 To provide a structural formation and association of parts in a machine of the above mentioned type, by which an effective compression and holding of the spring is attained in a rapid and certain manner during 20 an assemblage or a disassemblage of the component parts of said spring, all as will hereinafter more fully appear.

In the accompanying drawings:—

Figure 1, is a plan view embodying the 25 preferred form of the present spring compressing machine.

Fig. 2, is a front elevation of the same.

Fig. 3, is a side elevation of the same.

30 Fig. 3^a, is a detail side elevation showing the parts arranged for the manipulation of the valve springs of the cylinder head of an automobile engine.

Fig. 4, is a detail perspective view of one 35 form of the spring engaging jaws of the present structure.

Fig. 5, is a similar view of another form of said jaws.

Fig. 6, is a similar view of a spring holding saddle of the supporting table or bench 40 of the machine.

Fig. 7, is a similar view of a supporting bracket of said table or bench.

Fig. 8, is a detail front elevation illustrating the application of the present mechanism to an ordinary segmental axle spring. 45

Like reference numerals indicate like parts in the several views.

Referring to the drawings, 1 designates the main frame or standard of the machine, 50 which in the preferred form shown in the drawings comprises a series of vertical posts and horizontal rails rigidly connected together to constitute the rectangular skeleton structure shown.

55 2 designates a work supporting table or

bench secured to the front of the frame 1, preferably in a detachable manner by means of supporting end brackets 3 provided with engaging hooks and studs 4 adapted for engagement in vertical series of receiving 60 orifices 5 in the vertical posts of the main frame 1, so that a positioning of table or bench 2 at the required height may be effected when so desired.

6 designates removable spring holders 65 each of which has a main stationary member or head provided with a fixed upright jaw 7 and a plurality of depending studs 8 adapted for engagement in a plurality of sockets or orifices 9 formed therefor in the table or bench 2, so that the holder 6 may be located at any desired location on said table or bench.

10 designates an adjustable head or jaw 75 slidingly connected to the main head 6 aforesaid, and provided with a clamping bolt 11 or other like means for securing the parts at the required adjustment in relation to each other with the jaws 7 and 10 set to receive and laterally support a spring of a 80 specific width.

12 designates a vertically movable compression head or platen guided in vertical guideways on the main frame and having 85 superimposed relation to the table or bench 2 aforesaid.

13 designates a forwardly extending and horizontally arranged shank or stem carried by the head or platen 12 for the attachment 90 of different forms of spring engaging jaws or arms now to be described.

14 designates a spring engaging jaw or arm having at one end a tubular socket or sleeve 15 for engagement with the aforesaid shank or stem 13, and with a clamping screw 95 16 by which it is secured in place. At its other end the jaw 14 is formed with a spring engaging extension 17 which may be of a yoke shape as illustrated in Fig. 4, or an annular shape as illustrated in Fig. 5, or other suitable form as may be found desirable for a particular use.

The preferred means for imparting vertical movement to the compression head or platen 12 comprises parts as follows:

18 and 19 designate upper and lower shafts journaled on the main frame 1 and carrying pairs of sprocket wheels 20 and 21 for engagement with a pair of endless chains 22, which are in turn operatively connected 110

to the head or platen 12, to impart the required vertical movement to the same in either direction, in accordance with the direction in which the sprocket wheels and chains are moved by the operator.

23 designates a foot lever or treadle fixedly associated with the lower pair of sprocket wheels 21 and affording a positive means for turning said wheels in one direction.

10 24 designates a spring associated with the foot lever 23 and adapted to impart a rising movement to the foot lever when the foot of the operator is removed therefrom.

15 In the use of the present machine to manipulate the axle spring of the ordinary segmental leaf type shown in dotted lines in Fig. 8, or the centrally dished segmental leaf type shown in dotted lines in Fig. 2, and commonly known as the Ford spring, 20 the said spring will be arranged in the spring holders 6, said holders having been previously positioned on the table or bench 2.

25 The compression head or platen 12 is then moved down by the action of the foot lever 23, bringing a spring engaging jaw or arm 14 into forcible contact with the middle portion of the spring operated on, to effect a compression of the leaves of the spring, and 30 with the yoke or annular shaped ends 17 of said jaw straddling or encircling the nut or head of the central connecting bolt of the spring to permit a ready tightening movement of said nut in an assemblage of the 35 spring members, or a loosening of said nut in a disassembly operation on said spring members.

40 In the use of the machine to manipulate the valve springs of a multiple cylinder automobile engine, the said engine or the head carrying the valves of the engine, is positioned in the table or bench 2, the same having been previously adjusted on the main frame 1, so that the upper ends of the 45 valve springs will be in proper engaging position with the compression jaw 14, as shown in Fig. 3^a. The head or platen carrying said jaw 14, or a plurality of the same, is then moved down by the action of the 50 foot lever 23 bringing the spring engaging jaw or jaws 14 in contact with the top bearing washer or collar of the valve spring or springs to effect a proper compression of said spring or springs, with a forked end 55 17 of each jaw straddling the guide rod of a valve spring and with the confining cross-pin by which a washer or collar aforesaid is held in place in an exposed condition adapted for ready removal and replacement 60 as required. In the above described use of the present machine it is preferable to employ a plurality of compression jaws 14 corresponding in number with the number of cylinders of the engine operated on, with a 65 view to rapidity and economy of operation.

Having thus fully described my said invention what I claim as new and desire to secure by Letters Patent, is:—

1. In a spring compression machine, a main frame, a work table on said frame, a movable compression head guided in the main frame, a horizontal compressor jaw attached to said head in superimposed relation to the work table, a foot lever, and operative connections between said lever and 75 said compressor head.

2. In a spring compression machine, a main frame, a work table on said frame, a movable compression head guided in the main frame, a horizontal compressor jaw attached to said head in superimposed relation to the work table, a foot lever, and operative connections between said lever and said compressor head, the same comprising upper and lower wheels revolubly mounted on the 80 main frame, and operatively connected to the foot lever, and an endless chain connection carried by said wheels and operatively connected to said compressor head.

3. In a spring compression machine, a main frame, a work table on said frame, a movable compression head guided in the main frame, a horizontal compressor jaw attached to said head in superimposed relation to the work table and having a forked 90 engaging end, a foot lever, and operative connections between said lever and said compressor head.

4. In a spring compression machine, a main frame, a work table on said frame, a movable compression head guided in the main frame, a horizontal compressor jaw attached to said head in superimposed relation to the work table, spring holders 100 revolvably connected to the work table, a foot lever, and operative connections between said lever and said compressor head.

5. In a spring compression machine, a main frame, a work table secured in a vertically adjustable manner to the front of said 110 frame, a movable compression head guided in the main frame, a horizontal compressor jaw attached to said head in superimposed relation to the work table, a foot lever, and operative connections between said lever and the compressor head.

6. In a spring compression machine, a main frame, a work table on said frame, a movable compression head guided in the main frame and having a horizontally disposed carrying shank in superimposed relation to the work table, a spring engaging jaw having a socket at one end for engagement with the aforesaid carrying shank and having at the other end a yoke extension, a 120 foot lever, and operative connections between said lever and said compressor head.

Signed at Chicago, Illinois, this 17th day of April, 1920.

EDWARD M. REEVES.
